UNITED STATES PATENT OFFICE.

JOSEPH J. REILLY, OF NEWARK, NEW JERSEY.

WINDOW-CURTAIN FIXTURE.

1,350,336.

Specification of Letters Patent. Patented Aug. 24, 1920.

Application filed March 20, 1919, Serial No. 283,851. Renewed July 9, 1920. Serial No. 395,120.

To all whom it may concern:

Be it known that I, JOSEPH J. REILLY, a citizen of the United States, and resident of Newark, in the county of Essex and State 5 of New Jersey, have invented certain new and useful Improvements in Window-Curtain Fixtures, of which the following is a full, clear, and exact description.

This invention relates to a support for 10 roller shades and it has for an object to provide a simple and inexpensive device embodying a readily adjustable support, capable of accommodating rollers of different lengths without detachment from and re- 15 attachment to the window frame or other frame in which the shade is to be hung, and which renders unnecessary accurate fitting upon the window frame in order to properly engage the roller.

20 For further comprehension of the invention, and of the objects and advantages thereof, reference will be had to the following description and accompanying drawings, and to the appended claims in which the 25 various novel features of the invention are more particularly set forth.

Drawings.

Figure 1 of the drawings is a front view 30 of the upper portion of a window frame and window having the invention applied thereto.

Fig. 2 is an enlarged fragmentary front view, showing one of the supports with a 35 portion of the roller and the window frame.

Fig. 3 is a plan view of the parts shown in Fig. 2.

Fig. 4 is a similar view to Fig. 2, but with the roller removed.

40 Fig. 5 is a transverse section on the line 5—5 of Fig. 3.

Description.

In the drawings the upper portion of a 45 window frame and window of ordinary construction are indicated at 1 and 2 respectively.

My improved support comprises a pair of horizontal bars 4, disposed, one at each side 50 of the window extending both over a portion of the window frame and of the window sash and spaced outwardly from the window frame, as shown most clearly in Fig. 3.

To provide for this disposition of the bars 55 the end of each bar which extends across the window frame is inwardly offset, as

shown at 5, to lie against the frame and may be secured to the latter by screws 6, passing through suitable apertures formed therein. The opposite end of each bar is bent back 60 parallel to the main reach of the bar in alinement with the offset 5 as at 7, and has an angular foot 8, which engages the inner face of the window frame and may be secured thereto by one or more screws 9. 65

Upon this bar is slidably mounted a bracket 10, having its upper and lower edge bent over as at 11 and 12 to engage the inner face of the bar and so hold the plate thereon, this plate having an outwardly projecting 70 perforated ear 13, the whole constituting an adjustable bracket for supporting the roller.

Pivotedly secured at their inner ends as at 16, to the ears, are short arms 17, whose outer ends may be formed respectively with the usual slot and perforation adapted to receive the trunnions on the end of an ordinary spring roller or Hartshorn roller as it is generally called, and which, with the shade 80 wound thereon is indicated at 18. The inner end of each arm 17 is formed with a tail 19 which presents a vertical rear edge in engagement with the face of the bar 4, when the arm is in horizontal position, as clearly 85 shown in Fig. 5. The faces of the bars 4 may be formed with vertical indentations or serrations 20 in which the tails 19 engage

When the trunnions of the roller are placed in the ends of the arms 17, the weight 90 of the roller and shade will act to wedge or force the tails 19 into the indentations 20 and so lock the supporting bracket in position. While I have shown in detail only one of the supporting devices, it is to be 95 understood that the devices at each end of the roller are similar and the description and illustration of one is intended to include both.

To adjust the brackets to any desired position, it is only necessary to swing the arms 17 upwardly and slide the brackets 10 along the bars 4 to the desired position and then swing the arms downwardly causing the tails to engage in the indentations 20 and when the shade is placed in position, its weight will lock the brackets to the bars. 100 105

As will be apparent from the foregoing description, I have provided a simple and inexpensive support for a roller shade which 110 renders unnecessary an accurate fitting thereof to the window frame to secure

proper engagement with the roller trunnions and which may be adjusted with a minimum of trouble to support rollers of varying length.

5

Claims.

1. A fixture as characterized comprising, a plurality of horizontal bars, each adapted for disposition in service at one side of a window opening, the said bars having parallel spaced sections, one of said sections being longer than the other to rest in parallel relation to the window frame, both of said sections having offset portions to form securing members for mounting the sections and the bars on the window frame; and a sliding, adjustable bracket adapted for pivotally mounting the rotary window-sash roller.
- 10
- 15

2. A fixture as characterized comprising, 20 a plurality of horizontal bars for supporting a sliding bracket, said bars having parallel sections, and offset foot-like projections for mounting the bars on a window frame so that the end of the bar extends over the 25 window opening; and a plurality of adjustable brackets for a window shade.

3. A fixture as characterized comprising, 30 a plurality of supporting members, each having parallel bars disposed in spaced relation, one of said bars being longer than the other, each having offsets to form fastening members for securing the bars to the frame of a window so that said supporting bars may overhang the same across the open 35 space in the window.

JOSEPH J. REILLY.
